UNITED STATES PATENT OFFICE.

EDWARD A. BURNS, OF HARTFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed August 18, 1921. Serial No. 493,192.

To all whom it may concern:

Be it known that I, EDWARD A. BURNS, a citizen of the United States, residing in Hartford, in the county of Hartford and 5 State of Connecticut, have invented certain new and useful Improvements in Typewriting Machines, of which the following is a specification.

In typewriting machines, the types are 10 operated by key-levers which are usually provided with guides to support the levers against the lateral thrust of the fingers of the operator upon the keys; these guides being usually as close to the keys as possible to avoid lateral bending of the levers, which are usually made thin, and, consequently, laterally weak, to save weight. This invention relates to the construction 15 of the guide-comb.

It is the usual practice to punch or cut 20 lateral slots in a plate of metal to form it into the guide-comb, but this does not result in the production of guides of such smoothness as is needed for guiding key-levers, which have considerable length of 25 strokes, in which they are guided by the comb, so that any rough condition of the guide, such as will be due to punching out the slots, would prevent or would render 30 impossible the desired freedom of movement of the lever, which will make two strokes for every type impression, so that even little roughness at this point would make 35 a noticeable difference in the ease, liveliness and speed of the type-action, and even though this obstruction is trifling, still it would be multiplied because of the thousands of these strokes hourly which would be obtained during the operation of the 40 machine.

The main object of the invention is to provide at small cost a guide-comb having rigid teeth which are smooth on the lever-guiding surfaces.

To obtain this result, the teeth of the 45 comb are stamped out individually from sheet-metal, each tooth consisting of a blade or guide portion, and a hilt, tang or shank forming an attaching portion, whereby the teeth are made attachable at their 50 upper ends to a bar which forms the back or main portion of the comb, and by which the comb may be supported on the frame of the machine. One of the features of the invention is the construction of this bar, which

may be in the form of a sheet-metal strip having notches cut in its top and bottom edges to be utilized in attaching the teeth to the bar. Each tooth when stamped out is in the form of a blank of 60 considerable width, and has a blade portion which is folded longitudinally, so as to have two sides, these sides being the guiding surfaces for the key-levers and being exceptionally smooth, and, if desired, 65 may be subjected to smoothing and finishing operations after being folded, so as to eliminate every possible roughness. The head portion or hilt of the tooth is also folded together with the blade portion 70 thereof, and tongues, formed upon said head portion, project rearwardly in position to fit into the upper and lower notches in the bar. These tongues are then folded or pressed around the teeth or lugs formed 75 by the notches on the upper and lower edges of the bar. When these tongues are thus firmly clenched or closed over the teeth on the bar, the guiding tooth is rigidly supported and cannot become loose. The 80 width of the guiding tooth is considerable, and, owing to its channel shape, it is extremely rigid; while the whole device is very compact, occupying little, if any, more room than the usual punched-out comb, and 85 which will be a desideratum in a typewriting machine, especially near the keyboard thereof. The metal of the attached teeth may be relatively thin, whereby it can be punched and bent successfully and at low 90 cost, while it may also be of high grade and devoid of cutting edges or rough portions; while, owing to the aforesaid channel shape of the teeth, it has requisite stiffness notwithstanding its thinness. 95

Other features and advantages will hereinafter appear.

In the accompanying drawings,

Figure 1 is a front-to-rear vertical section of the lower and forward part of an Underwood typewriting machine having the guide-comb of the present invention embodied therein. 100

Figure 2 is an enlarged front perspective view of the left end part of the guide-comb 105 as viewed from the right and above.

Figure 3 is a rear elevation of what appears in Figure 2, with the addition of two of the key-levers shown in transverse section.

Figure 4 is a rear perspective view of one of the comb teeth before its attachment to the comb-back or bar.

Figure 5 is a plan view of a stamped-out blank from which the tooth shown in Figure 4 may be formed.

In the accompanying drawings, the invention is shown as embodied in a standard Underwood typewriting machine having type-
10 keys 1 carried by the forward free ends of usual flat and comparatively thin metal key-levers 2, which, at their rear ends, may be suitably pivoted in a usual machine frame 3. In the Underwood typewriting machine, the
15 guide-comb for supporting the key-levers 2 against lateral thrust is located just at the back of the upper or rearmost row of keys 1, and that is the location of the improved guide-comb of the present invention.

20 According to the present invention, the guide-comb comprises a comparatively thick and strong sheet-metal strip or flat bar 4, which forms the back of the comb, and at its opposite ends is provided with holes 5, one of
25 which appears in Figures 2 and 3, and by means of which the comb may be firmly secured in place in the usual way on the machine frame 3. As a means for attaching the individual lever-guiding teeth to the
30 comb-back 4, this back or supporting bar is provided with openings, shown in the form of notches 6 punched or cut along its upper edge, and similar diametrically opposite openings or notches 7 are provided along
35 its lower edge, so as to leave upwardly-projecting teeth or lugs 8 between the upper notches 6, and similarly to leave downwardly-projecting teeth or lugs 9 between the lower notches 7.

10 In forming the individual comb teeth, blanks, such as the one shown in Figure 5, are stamped out of relatively thin sheet-metal, considerably thinner than the metal plate or strip from which the comb-back or
45 tooth-carrying supporting bar 4 was formed. Each of these blanks is of considerable width and has a lower comparatively wide blade portion 10 and an upper attaching portion or hilt comprising a comparatively
50 narrow tang or shank 11, at the upper end of which there are provided a pair of tongues 12 appearing in the blank as oppositely-extending wings, and at its lower end, adjacent to the plate 10, the tang or shank
55 11 is provided with a similar pair of tongue-forming wings 13. By a second stamping operation the flat blank shown in Figure 5 is bent or folded longitudinally throughout its length to the form shown in Figure 4,
60 in which the two pairs of tongues 12 and 13 project rearwardly, and in which the lateral margins or edge portions at the plate 10 extend rearwardly in the form of flanges 14, so that the guide blade 10 is now of channel
65 shape. It is to be noted that the lower pair

of attaching tongues 13 are continuous with the upper ends of the channel sides or flanges 14, thereby considerably strengthening the comb tooth at its point of attachment, where strength is most needed.

In the assembling operation, the upper pair of rearwardly-projecting attaching tongues 12 are inserted into adjacent notches 6 to embrace one of the lugs 8 on the upper edge of the comb-back or bar 4, and the lower pair of rearwardly-projecting attaching tongues 13 are similarly inserted in adjacent notches 7 to embrace an intervening lower lug 9 on the bar 4, the tang or shank 11 of the attaching portion of the comb-back now lying flat against the front face of the bar 4. Next, by a further stamping or pressing operation, the two pairs of rearwardly-projecting attaching tongues 12 and 13 are clenched or turned over inwardly into firm contact with the rear faces of the lugs 8 and 9, respectively, the ends of the folded tongues 12 now forming terminal hooks 15 and the folded ends of the tongues 13 forming similar hooks 16, as shown in Figures 2 and 3, whereby the lever-guiding comb teeth are firmly and rigidly supported upon the comb-back or bar 4.

The outer surfaces of the lever-guiding flanges or sides 14 will present all of the smoothness of the smoothly finished sheet-metal from which the original blanks, such as shown in Figure 5, have been stamped, so that the key-levers 2 will move freely and easily between the guiding surfaces of the channel-shaped guide blades 10 of adjacent comb teeth, as shown in Figure 3. In the normal position of the key-levers 2 appearing in Figures 1 and 3, the upper margins or edges of these levers enter into the notches 7 between the lower attaching tongues 13 of adjacent comb teeth, these tongues 13, as hereinbefore noted, forming at their base continuations of the guide flanges 14.

The improved comb of the present invention is mounted on the machine frame 3 similarly to the usual punched-out comb heretofore employed, that is to say, the comb-back or tooth-carrying supporting bar 4 extends transversely across the frame 3 just above the key-levers 2 immediately at the rear of the upper or rearmost row of keys 1, and the lever-guiding channel-shaped comb teeth, each comprising the guide blade 10 having the rearwardly-extending guide flanges 14, project downwardly between the key-levers 2 from the lower edge of the flat comb-back or supporting bar 4.

Variations may be resorted to within the scope of the invention, and portions of the improvements may be used without others.

Having thus described my invention, I claim:

1. A guiding comb for key-levers, comprising a flat supporting bar provided with

- openings, and individual comb teeth having a lever-guiding blade portion provided with turned-over edges to form smooth guiding surfaces and having an attaching portion 5 provided with attaching tongues passing through said opening and turned-over or clenched to secure the teeth upon the bar.
2. A guiding comb for key-levers, comprising a flat supporting bar provided with 10 lateral notches, and individual comb teeth having a lever-guiding blade portion provided with turned-over edges to form smooth guiding surfaces, and having an attaching portion provided with attaching tongues 15 engaging in said notches and clenched at their ends to secure the teeth on the bar.
3. A guiding comb for key-levers, comprising a flat comparatively thick and strong supporting bar provided at its opposite 20 edges with notches, and individual lever-guiding teeth of comparatively thin material having each a blade or guiding portion of channel shape of which the flanges of the channel form the guiding surfaces, and having 25 an attaching portion provided with an upper pair of attaching tongues engaging in the notches in the upper edge of the supporting bar, and having a lower pair of attaching tongues engaging in the notches in 30 the lower edge of the supporting bar, the ends of said tongues being turned over or clenched to secure the tooth in place on the bar.
4. A guiding comb for key-levers, comprising a flat comparatively thick sheet- 35
- metal supporting bar provided in its opposite edges with notches forming lugs, and individual lever-guiding teeth of comparatively thin sheet-metal and each having a guiding blade of channel form of which the 40 sides or flanges of the channel form the guiding surfaces, and having an attaching portion provided at its free end with a terminal pair of attaching tongues bent around one of said lugs on the bar, and provided 45 with a second pair of attaching tongues formed continuous with the flanges of the channel forming the blade and bent around one of said lugs at the opposite edge of said bar. 50
5. The combination with a bank of key-levers operatively mounted in a machine frame, of a lever-guiding comb comprising a flat com-bar adapted to be attached at its end to said frame, said comb-bar having 55 notches in its opposite edges, and lever-guiding comb teeth formed of sheet-metal each having a guide blade provided with turned-over edges forming smooth guiding surfaces, and each tooth having an attaching 60 portion lying against one of the flat sides of the bar and provided with attaching tongues engaging in the notches at the opposite edges of said bar, said tongues being turned over or clenched to secure the tooth 65 firmly in place on said bar.

EDWARD A. BURNS.
